ACYLATION OF DIARYLGUANIDINE SALTS
OF DIAMINO DIBENZOTHIOPHENEDIOXIDE SULFONIC ACIDS

Hans Z. Lecher, Plainfield, and Dale R. Eberhart, Bound Brook, N. J., assignors to American Cyanamid Company, New York, N. Y., a corporation of Maine

No Drawing. Original application April 4, 1950, Serial No. 153,992. Divided and this application April 26, 1951, Serial No. 223,174

7 Claims. (Cl. 260—329.3)

1

The present invention relates to the acylation of aminosulfonic acids. More particularly, it is concerned with the acylation of aminosulfonic acids of the dibenzothiophenedioxide series. Specifically, this case is concerned with the acylation of diarylguanidine salts of those acids. As such this application is a division of our application for United States Letters Patent, Serial No. 153,992, filed April 4, 1950.

Many of these compounds possess marked fluorescent properties and are particularly useful to overcome the yellowish cast which is caused by various factors in many different white materials, especially cellulosic fabrics. These compounds, however, are not claimed per se in the present application. They form in part the subject matter of the copending applications of Scalera and Eberhart for United States Letters Patent, Serial No. 45,425, filed August 20, 1948; and Serial No. 168,392, filed June 15, 1950.

Despite their desirability in use, the commercial exploitation of these materials has been hampered by the lack of a generally suitable acylation method of preparing them. It has been found that the known methods of acylation are not suitable for industrial development when an attempt is made to apply them to these materials. Many difficulties are encountered.

For example, while many amino compounds are readily acylated with acid halides in aqueous solution, 3,7-diaminodibenzothiophenedioxide-2,8-disulfonic acid, cannot be acylated at all in this way. Attempted reaction gives little or none of the desired product, the acid halide instead being mostly destroyed by hydrolysis. In still other cases, where the halide may not be quite so sensitive, and is not destroyed so rapidly or completely, the results are unsatisfactory for other reasons.

Non-polar organic solvents have been used successfully in many similar types of acylations. However, they have not been utilized with these aminosulfonic acids. Neither the free acids nor their metal salts can be satisfactorily acylated in an organic medium. Their solubility is too low. Further, the amino groups of the free acid are rendered comparatively inert to acylation under these conditions. This appears to be due to association with the sulfonic acid groups in Zwitter ion form which appears to resist the action of the acyl halide.

If these difficulties could be successfully overcome, there would exist a demand for both the successful procedure and its products. It is, therefore, the principal object of the present in-

vention to devise an acylation method suitable for use with these compounds for which the known procedures were not satisfactory.

In general, the object of the present invention has been accomplished by carrying out the reaction in a non-polar solvent with certain organic base salts of the amino sulfonic acids. In view of the difficulties encountered in the past, the effectiveness of the process of the present invention is particularly surprising, especially with those compounds, such as alkoxy-substituted benzoyl halides, that are exceptionally difficult to use because of their unusual sensitivity. In all cases, the products are obtained in satisfactory quality and yield.

The use of these organic base salts, in place of the free acids or their alkali metal salts, apparently has the effect of breaking up the stable Zwitter ion structure of the aminosulfonic acid, and of enhancing the solubility in the solvent. In any case, the desired acylation is accomplished by converting the aminosulfonic acid to its salt with the organic base and treating the resultant salt with the acyl halide in a non-polar solvent.

In accordance with the present invention, symmetrical diaryl guanidines have been found very suitable for this salt formation. They readily form well-defined crystallizable salts with the dibenzothiophene dioxide aminosulfonic acids of the present invention. These salts are smoothly acylated in organic solvents. After acylation is complete, the reaction mixture is made alkaline, breaking down the diaryl guanidine salt of the product. A particularly useful solvent is nitrobenzene, permitting an easy recovery of both the reaction product and the diarylguanidine. The reaction product is made alkaline with an organic alkali salt, for example sodium acetate, potassium propionate, sodium ethylate, sodium phenoxide, sodium lactate, potassium p-chlorophenoxy, and the like. The nitrobenzene retains the diaryl guanidine in solution and permits its removal with the organic solvent; the acylated sulfonic acid is out of solution as the alkali salt and can be isolated by known methods.

While a wide variety of aminosulfonic acids may be acylated by the method of the present invention, it is particularly applicable to the aminosulfonic acids of the dibenzothiophene series, such as 3,7-diaminodibenzothiophenedioxide-2,8-disulfonic acid and its alkyl and chloro derivatives.

A wide variety of symmetrical diaryl substituted guanidines can be used successfully in the process of the present invention. Among these may be included diphenylguanidine, phenyl-o-

tolylguanidine, di-o-tolylguanidine, di-p-tolylguanidine, dixylylguanidines, phenyl-p-anisylguanidine, benzylidiphenylguanidine, bis-p-chloro-phenylguanidine, di-o-anisylguanidine, di-p-phenetylguanidine, dinaphthylguanidine, and di-2-pyridylguanidine.

A number of solvents are suitable for the purpose of carrying out the acylation process of the present invention. It is essential that they have solvent action on the product and that they be stable to the reactants. In general, organic solvents boiling above about 120 degrees C. are to be preferred. Suitable solvents include both aliphatic and aromatic hydrocarbons and their halogeno and nitro derivatives, as well as esters, ethers, and ketones. By way of specific example, the following solvents are effective: mono- and dichlorobenzene and the chlorotoluenes; the xylenes; nitrobenzene and the nitrotoluenes; cymene, acetylene tetrachloride, acetophenone, cyclohexanone, and anisole.

It is an advantage of the present invention that the salts can be prepared by any suitable method. For example, the aminosulfonic acid can be dissolved in water, neutralized, and treated in aqueous solution with a soluble salt of the guanidine. The desired salt crystallizes directly from the solution. It is not necessary for the purpose of this invention that the salt be strictly pure or dry. It is dispersed in the selected organic solvent. A convenient practice at this point is to remove any water present by distilling a part of the solvent. Acylation is then readily effected by adding the acyl halide to the mixture.

A suitable acyl halide may be selected from a wide variety of aliphatic and aromatic carboxylic acids. These include, for example, benzoyl chloride and its alkylated, nitrated, and halogenated derivatives; butyryl chloride, ethanesulfonyl chloride, chloroacetyl chloride, crotonyl chloride, propionyl bromide, p-toluenesulfonyl chloride, thiophene-2-carboxylic acid chloride, alpha-naphthoyl chloride, 2-hydroxy-3-naphthoyl chloride, benzoyl bromide, nicotinyl chloride and acetylulfanilyl chloride, as well as such bifunctional compounds as terephthaloyl chloride, succinoyl chloride, and adipoyl chloride. As has been mentioned, the process of the present invention is particularly useful in utilizing the acid chlorides of alkoxy-substituted benzoic acids, such as the isomeric anisoyl chlorides, o-ethoxybenzoyl chloride, o-propoxybenzoyl chloride, and 2,4- and 2,5-dimethoxy benzoyl chlorides.

Example 1

A solution is prepared from 26.3 parts of di-o-tolylguanidine, 11.9 parts of concentrated hydrochloric acid, and water to the volume of 200 parts of water. This is slowly added to a solution prepared by adding 20.3 parts of 3,7-diaminodibenzothiophenedioxide 2,8-disulfonic acid to 100 parts of water, neutralizing with 5 N sodium hydroxide solution, and diluting to the volume of 200 parts of water. The salt which crystallizes out is filtered, washed, and dried.

A mixture of 7.2 parts of benzoyl chloride, 50 parts of chlorobenzene, and 4.4 parts of the above prepared di-o-tolylguanidine salt is gradually heated. Condensation begins at about 120 degrees C., as evidenced by hydrogen chloride evolution, and is complete at reflux. The reaction mixture is then cooled, and neutralized by the addition of 11.3 parts of phenol in 29 parts of 5 N sodium hydroxide solution. The product is stirred, filtered and washed with nitrobenzene. It is then slurried in water and salt, boiled to remove traces of nitrobenzene, cooled, filtered, washed and dried.

The di-o-tolylguanidine is retained in the nitrobenzene solution and is readily recovered for re-use by steam distillation to remove the nitrobenzene.

Example 2

A mixture of 24 parts of nitrobenzene and 4.4 parts of the di-o-tolylguanidine salt, prepared as described in Example 1, is heated to 120 degrees C. and treated with 2.5 parts of cinnamoyl chloride. The mixture is then heated further to 140 degrees C. to complete the reaction, cooled to 85 degrees C., and treated with a solution of 1.9 parts of phenol in 5 parts of 5 N sodium hydroxide. The resulting bright yellow precipitate is filtered, washed with nitrobenzene and acetone and dried.

Example 3

The di-o-tolylguanidine salt of 3,7-diaminodibenzothiophenedioxide 2,8-disulfonic acid is prepared according to the procedure described in Example 1. This salt (8.8 parts) is heated at 150 degrees C. in 48 parts of nitrobenzene with 8.3 parts of 2,4-diethoxybenzoyl chloride until a test for primary amino groups becomes negative. The resulting mixture is treated at 148-50 degrees C. with 8.0 parts of finely powdered anhydrous sodium acetate. After being stirred approximately two hours at this temperature, the mixture is cooled, filtered, and washed with 48 parts of nitrobenzene. The product is slurried in water, freed of nitrobenzene by steaming, filtered and dried.

Example 4

The acylation reaction of Example 3 is repeated. The reacted mixture is cooled to 70 degrees -80 degrees C. and treated with a solution of eight parts of 5 N sodium hydroxide solution in eight parts of alcohol. The rest of the product is worked up as in Example 3, and results in an excellent yield of very pure product.

Example 5

Example 3 is repeated substituting for the di-o-tolylguanidine salt in that procedure 8.5 parts of the corresponding diphenylguanidine salt, prepared by adding an aqueous solution of diphenylguanidine hydrochloride to the sodium salt of 3,7-diaminodibenzothiophenedioxide 2,8-disulfonic acid. On working up the product as in Example 3 an excellent yield of suitably pure product is obtained.

Example 6

5

A solution of 20.7 parts of p-hydroxybenzoic acid in 100 parts of water containing 12 parts of sodium hydroxide, is gradually treated at 25 degrees C. with 34.4 parts of p-toluenesulfonyl chloride. Alkalinity is maintained by the simultaneous addition of approximately 2.4 additional parts of sodium hydroxide. The product is then precipitated with acetic acid, filtered, washed, and dried at 60 degrees C. 5.8 parts of the p-tosyloxybenzoic acid, thus prepared is converted to acid chloride in the usual way with 3.6 parts of thionyl chloride. Excess thionyl chloride is removed in a stream of air. 2.5 parts of the resulting acid chloride is added at 80 degrees C. to 12 parts of nitrobenzene containing 2.2 parts of the di-o-tolylguanidine salt prepared as in Example 1. The reaction is completed at 240 degrees C., the mixture then being cooled to 75 degrees C. and neutralized with a solution of 0.94 part of phenol in 2 parts of 5 N sodium hydroxide solution. The product is filtered, washed with nitrobenzene followed by acetone, and dried at 110 degrees C.

Example 7

15.2 parts of p-anisic acid is added gradually to 58 parts of chlorosulfonic acid at 5-11 degrees C. After one-half hour the mixture is gradually warmed to 75 degrees C. and maintained at this temperature one hour. It is then cooled, drowned in ice, and filtered. 2.9 parts of the resulting sulfonyl chloride is treated with 8 parts of morpholine. The reaction mixture is slowly treated with 5 N sodium hydroxide, the temperature rising to 25 degrees C. After acidification with hydrochloric acid, the 2-methoxy-5-carboxybenzene sulfonyl morpholine is filtered. It melts at 218-219 degrees C.

2.6 parts of this product is converted to the corresponding carboxylic acid chloride by treatment with 1.6 parts of thionyl chloride, in the usual manner. This is then added to a mixture of 12 parts of nitrobenzene and 2.2 parts of the di-o-tolylguanidine salt prepared in Example 1. After twenty minutes at 140 degrees-145 degrees C., the mixture is treated with a solution of 0.9 part of phenol in 2 parts of 5 N sodium hydroxide, with immediate formation of a yellow precipitate. The product is filtered hot, washed with nitrobenzene followed by acetone, and dried.

The analogous disulfonanilide, which has similar properties, is obtained in a similar way, sub-

6

stituting aniline for morpholine in the above procedure.

While the foregoing examples produce sodium salts rather than free acids, this does not interfere with utilization of the product. The salts may be converted to the acids and vice versa by any of the usual methods. The other alkali metal and ammonium salts may be prepared from the acid. In any case, since the compounds will be most often employed with soap or other alkaline materials, it makes little difference whether a salt or the acid is the starting material, since the free acid will probably be converted to a salt in that use.

We claim:

1. The method of acylating a sulfonic acid of 3,7-diaminodibenzothiophenedioxide, which comprises heating a mixture comprising a symmetrical-diarylguanidine salt of the selected aminosulfonic acid, an acid halide, and an inert organic solvent.

2. A process according to claim 1 in which, after completion of the reaction, the product is

precipitated by treatment with an alkaline-reacting organic metal salt.

3. A process according to claim 1 in which the organic solvent is nitrobenzene.

4. A process according to claim 1 in which the symmetrical diarylguanidine is symmetrical diphenylguanidine.

5. A process according to claim 1 in which the acid halide is an aryl chloride.

45 6. A process according to claim 5 in which the aryl chloride is an alkoxy-substituted benzoyl chloride.

7. A process according to claim 1 in which the symmetrical diarylguanidine is symmetrical di-o-tolylguanidine.
